REFRIGERATION

Curtis C. Coons, North Canton, and William H. Kitto, Canton, Ohio, assignors to The Hoover Company, North Canton, Ohio, a corporation of Ohio

Application July 20, 1938, Serial No. 220,187
In Great Britain August 20, 1937

16 Claims. (Cl. 62—119.5)

This invention relates to refrigerating systems and more particularly to evaporators designed for use in absorption refrigerating systems.

In refrigerating systems as hertofores constructed, the refrigerating fluid flowed downwardly through the evaporator by gravity. We have discovered an entirely new principle of evaporation wherein the refrigerant fluid is caused to circulate upwardly through the evaporator against the force of gravity by the energy supplied from a propelled stream of inert gas flowing through the evaporator. The broad aspects of this principle are disclosed and claimed in our co-pending application, Serial No. 220,189, filed July 20, 1938.

The present invention is concerned with an evaporator in which the liquid flows in paths both parallel to and counter to the inert gas stream.

While it is possible to drag or sweep the liquid refrigerant from the lowest to the highest portions of the evaporator, it is not always desirable to do so. It may be necessary to construct portions of the evaporator of conduit section of large diameter—so large that the inert gas velocity is not high enough to drag or sweep the liquid refrigerant through the conduit. It is sometimes necessary or desirable to supply the liquid refrigerant to an intermediate portion of the evaporator to meet structural difficulties. Also it is sometimes necessary to extend the evaporator a considerable distance above and below the bottom of the condenser while making a short direct connection between the evaporator and the condenser. The present invention is designed to meet the above enumerated difficulties in a simple manner.

We have further discovered that a refrigerating system embodying an evaporator in which the liquid is dragged or swept therethrough by a propelled stream of inert gas is self-regulating for atmospheric temperature changes. That is, the system automatically regulates itself to compensate for internal changes induced by variations in atmospheric temperature conditions. This renders unnecessary the complex and expensive auxiliary equipment previously used to accomplish this result.

Our present evaporator is so designed that a portion of the liquid refrigerant supplied thereto flows downwardly counter to the stream of inert gas while the remainder of the liquid refrigerant is dragged or swept upwardly through the evaporator with the inert gas stream.

The refrigerating system herein disclosed provides refrigeration at a plurality of temperature levels whereby to provide low temperature freezing zones and higher temperature air-cooling zones.

Other objects and advantages of the invention will become apparent as the description proceeds when taken in connection with the accompanying drawing in which:

- 5 Our invention is diagrammatically illustrated as being applied to a three-fluid absorption refrigerating system having the evaporator thereof shown in perspective and on an enlarged scale.
- 10 We have illustrated our invention as applied to a continuous three fluid absorption refrigerating system comprising a boiler B, an analyzer D, a rectifier R, a condenser C, an evaporator E, an absorber A, and a pressure equalizing medium circulating fan F driven by a motor M. With the exception of the evaporator E, all elements of this system are illustrated diagrammatically, it being understood that they may be of any specific construction or form desired.
- 15 The elements just described are suitably connected by various conduits to form a complete refrigerating system including a plurality of gas and liquid circuits. The system is suitably charged with a refrigerant, such as ammonia, an absorbent such as water, and a pressure equalizing medium, preferably a dense inert gas such as nitrogen. Thus the ammonia and water perform the usual functions of refrigerant and absorbent in absorption refrigerating apparatus.
- 20 Thus pressure equalizing medium, nitrogen in this case, however, which is present only in the evaporator-absorber parts of the system and circulates in a circuit between these elements, serves to permit the entire system to operate at substantially the same pressure while reducing the vapor pressure of the refrigerant in the evaporator wherefore the refrigerant will evaporate just as though the actual pressure prevailing in the evaporator was materially below the condenser pressure. Therefore, no pressure differential need be maintained between the absorber and generator because the inert pressure equalizing medium present in the absorber permits the same to operate at an actual total pressure equal to that prevailing in the generator but operates with respect to the refrigerant as though the absorber pressure were much below that prevailing in the generator.
- 25 The boiler B is heated in any suitable manner as by a gas burner or an electric cartridge heater. The source of heat for the boiler and the electrical motor M are controlled in any suitable or approved manner. A suitable control mechanism is disclosed in the co-pending application of Curtis C. Coons, filed June 17, 1937, Serial No. 148,424.

The boiler B contains a solution of refrigerant in an absorbent which will liberate refrigerant vapor when heated. Refrigerant vapor generated in the boiler B passes upwardly through

the analyzer D in counterflow relationship to strong liquor flowing downwardly therethrough. Absorption solution vapor liberated in the boiler B is condensed in the analyzer, the heat of condensation serving to generate more refrigerant vapor from the strong solution in the analyzer. The refrigerant vapor passes from the analyzer to the condenser C through a conduit 11 which includes the air-cooled rectifier R. The rectifier condenses any absorption solution vapor which may pass through the analyzer.

The boiler-analyzer system B—D and the absorber A are connected by suitable conduits to form a solution circuit. Weak solution is conveyed from the boiler B through a conduit 12, liquid heat exchanger 13, and a conduit 14 to the upper end of the absorber A through which it flows by gravity. It is apparent that the absorber A is at an elevation higher than that of the boiler-analyzer system whereby the weak solution must be elevated through the conduit 14. For this purpose a small gas bleed-off conduit 15 is connected between the discharge conduit 16 of the fan F and the conduit 14 below the liquid level of the boiler-analyzer system whereby the liquid is elevated through the conduit 14 by gas lift action. As the solution flows downwardly through the absorber its concentration is increased and the resulting strong solution is discharged from the bottom of the absorber through a conduit 17 into a strong solution reservoir 18. The strong solution is conveyed from the reservoir 18 to the liquid heat exchanger 13 by a conduit 19. Strong solution is returned from the liquid heat exchanger 13 to the upper portion of the analyzer D by a conduit 20.

The absorber and the evaporator are interconnected to form a pressure equalizing medium circuit. The pressure equalizing medium under pressure discharged from the fan F through the conduit 16 is conveyed into a gas heat exchanger 22. The gas is conveyed from the gas heat exchanger 22 into the bottom of the evaporator E through a conduit 23. The gas passes upwardly through the evaporator E in a manner to be described more fully hereinafter and exits therefrom through a conduit 24 into the gas exchanger 22. The gas discharged from the evaporator is conducted from the gas heat exchanger to the bottom of the absorber by a conduit 25. After passing through the absorber A, the pressure equalizing medium is returned to the suction inlet of the fan F through the conduit 26, thus completing the pressure equalizing medium circuit.

The refrigerant vapor supplied to the condenser C, which extends well below the top of the evaporator, is liquefied therein preferably by heat exchange with the ambient air. The liquid refrigerant is conducted from the condenser into the evaporator through a conduit 27.

For the present it is sufficient to say that the liquid refrigerant supplied to the evaporator evaporates into the pressure equalizing medium passing therethrough to produce refrigeration. The evaporation of the liquid refrigerant produces a mixture of pressure equalizing medium and refrigerant vapor which is conducted through the conduit 24, gas heat exchanger 22 and conduit 25 to the bottom of the absorber A. The mixture passes upwardly through the absorber in counterflow relationship to the solution flowing downwardly therethrough whereby the refrigerant vapor is absorbed in the solution and returned to the boiler in the manner previously de-

scribed. The purified pressure equalizing medium is then conducted to the circulating fan F from which it is propelled back to the evaporator through the conduit 16, gas heat exchanger 22 and conduit 23.

Referring now to the evaporator E in detail, it will be seen that it comprises a plurality of vertically spaced horizontal coil sections 30, 31, and 32 and a box-cooling section 33 which is provided with a plurality of air-cooling fins 34. The coil sections 30 and 31 are identical in shape but the conduits forming the coil section 30 are of an appreciably larger diameter for a purpose to be explained hereinafter. The coil section 30 only will be described in detail, it being understood that the description will apply equally well to the coil section 31. The coil section 30 comprises four spaced parallel horizontal conduit elements. The outer conduit elements 35 and 36 are serially connected by a conduit 37 extending across the rear of the evaporator. The inner conduits 38 and 39 are serially connected to the outer conduits 35 and 36, respectively, at the front portion of the evaporator. The inner conduits 38 and 39 form the inlet and outlet connection of the coil section. The top coil section is identical in shape with the coil section 30 except that it is not provided with a member corresponding to the conduit section 39, instead, the outer conduit thereof corresponding to the conduit 36 is connected to the front end of the box-cooling evaporator section 33 by means of a curved riser conduit 40. The outlet of the coil section 30 is connected to the inlet of the coil section 31 by a riser conduit 41. The riser conduit 41 comprises a pair of interfitting sections 51 and 52. The section 51 forms a continuation of the conduit 39 of the coil section 30 and extends a substantial part of the distance between the coil sections 30 and 31. The section 52 forms a continuation of the conduit 39 of the coil section 31 and extends downwardly into the section 51 for a purpose to be described hereinafter. The outlet of the coil section 31 is connected to the inlet of the coil section 32 by a riser conduit 42.

The evaporator just described is well adapted to be enclosed in a casing with the coil sections 30 and 31 forming shelves upon which ice trays or ice tray supporting plates may be supported conveniently.

The lean gas conduit 23 is connected to the inlet conduit 38 of the bottom coil section 30 of the evaporator E and the box-cooling section 33 of the evaporator is connected to the rich gas conduit 24 whereby the pressure equalizing medium travels continuously through the evaporator from the bottom to the top thereof.

The liquid refrigerant supplied to the conduit 27 is conducted into the riser conduit section 52 just above the point at which it enters the conduit section 51.

A drain conduit 45 is connected to the strong solution conduit 19 and the bottom portion of the inlet conduit 38 adjacent its point of connection with the gas supply conduit 23. Foreign matter, such as absorption solution, and excess liquid refrigerant which find their way into the evaporator are disposed of through the drain conduit 45 or are swept into the absorber with the rich gas from the evaporator.

When the refrigerating system is operating, the pressure equalizing medium is placed under pressure by the fan F whereby it is caused to circulate through the system with considerable velocity. The pressure equalizing medium circulating through the relatively large conduit

forming the coil section 30 is travelling at a relatively low velocity as compared with that prevailing in the higher portions of the evaporator. This difference in the rate of flow of the gas stream is due to the difference in the internal cross sectional area of the various parts of the evaporator. The liquid refrigerant which is supplied through the conduit 27 partly flows downwardly through the riser conduit 52 and through the lowest coil section 30 in counterflow relationship with the inert gas stream passing therethrough. The balance of the liquid refrigerant supplied to the riser conduit 41 is dragged or swept by the inert gas stream into the coil section 31. The gas stream is moving at a relatively high velocity through the coil sections 31 and 32 and the riser conduits 42 and 40 whereby it is able to drag or sweep liquid refrigerant through these coil sections and riser conduits into the box-cooling conduit section 33.

A divided body of liquid refrigerant is supported in the riser conduits through which the inert gas drags or sweeps its way carrying liquid refrigerant into the next higher evaporator section. The riser conduit 52 is continued downwardly into the conduit system 30 and 51 a distance just sufficient to permit the inert gas to support a liquid column in the section 52 whereby a part of the liquid supplied to the section 52 is dragged or swept into the coil section 31 and a part falls into the enlarged coil section 30. The velocity of the inert gas flowing in the large diameter coil section 30 is not sufficient to drag or sweep the refrigerant liquid along with it whereby the liquid counterflows with respect to the gas stream. The liquid in the coil section 30 evaporates into the inert gas stream; any impurities and excess liquid refrigerant are disposed of through the drain 45.

In order to produce refrigeration efficiently and at the temperatures necessary to freeze ice and to preserve foodstuffs in domestic refrigerating cabinets, it has been found advantageous to circulate the inert gas through the evaporator under conditions such that the volume of the inert gas will be several hundred times the volume of liquid refrigerant supplied to the evaporator per unit of time. Consequently, the velocity of flow of the inert gas through the evaporator will be materially greater than the velocity of flow of the liquid refrigerant. This evaporator meets that condition ideally while circulating the liquid refrigerant upwardly through all portions of the evaporator. Several factors have a material bearing on the design of an apparatus which will produce the desired conditions. The lifting power of the inert gas stream is a function of its density, pressure, and velocity of flow through the evaporator. In general, an increase in the value of any one or more of the above enumerated factors results in an increase in the lifting power of the inert gas. Other things being equal, the velocity of the inert gas will be a function of the effective cross-sectional area of its path of flow; an increase in effective cross-sectional area of that path resulting in a decrease in gas velocity. For example, it has been found that a propelled stream of nitrogen will circulate liquid ammonia upwardly through an evaporator constructed of approximately one-half inch inside diameter tubing and having a vertical height of approximately ten inches, a pressure differential of between two and four inches of water between the gas inlet and outlet connections to the evapo-

rator, and with the total system pressure ranging between 270 and 400 pounds per square inch. The above dimensions are cited by way of example only and are not limiting in any sense.

The leanest gas is supplied to the bottom portion of the evaporator but only sufficient liquid refrigerant flows downwardly from the liquid inlet to produce the desired amount of refrigeration therein. The refrigerant vapor pressure of the gas stream flowing upwardly through the evaporator progressively increases whereby evaporation occurs in the box-cooling conduit 33 at a temperature sufficiently high to prevent or minimize frost deposition thereon.

The bodies of liquid present in the various parts of the evaporator coils and particularly in the riser conduits have a marked throttling effect on the inert gas stream; furthermore this throttling effect is more noticeable at low pressures than at high pressures. This factor makes the system self-regulating for external atmospheric temperature conditions for the following reasons: A rise in atmospheric temperature decreases the efficiency of the absorber whereby the ammonia vapor pressure of the inert gas stream discharged from the absorber increases; this means that a given quantity of inert gas is now able to pick up a lesser quantity of ammonia vapor thereby decreasing the amount of refrigeration available. But an increase in the temperature of the atmosphere causes an appreciable increase in the pressure of the fluids in the system. This increases the density of the gas in the pressure equalizing medium circuit. As the density of the pressure equalizing medium increases, the circulating fan causes it to be placed under a higher pressure and to circulate at a higher velocity. Therefore, an increase in the temperature of the atmosphere decreases the efficiency of the absorber but automatically causes a greater quantity of inert gas to be circulated through the evaporator whereby refrigerating capacity is maintained under all atmospheric conditions.

The liquid progressively and continuously diffuses or evaporates into the inert gas stream to produce refrigeration whether it is travelling in parallel flow or counterflow relationship therewith. Preferably the supply of refrigerant liquid is so proportioned that all portions of the evaporator are active, but without permitting liquid refrigerant to be swept into the gas heat exchanger or to flow into the drain conduit 45.

The action of the inert gas on the liquid refrigerant may be briefly described as follows: In substantially horizontal conduits the gas stream flows over a stream of liquid in the bottom portion of the conduit to which it imparts a propelling force by the frictional drag of the gas stream as it passes over the liquid. Additionally, the dragging action of the gas on the liquid serves to agitate the liquid stream which improves the gas and liquid contact therebetween and aids the evaporating process. In the elevating or rising conduits, the gas stream supports a body of liquid in a divided state through which the gas continuously forces itself agitating such body of liquid and blowing or dragging a portion thereof into the next evaporator conduit. Though the gas is described herein as travelling at a high velocity, this term is to be understood in a relative sense because the velocity of the gas will depend upon the conditions prevailing in the particular system as noted above; for example, in the particular embodiment of the in-

vention disclosed herein, the velocity of gas flow through the evaporator is of the order of a few feet per second if a dense gas, such as nitrogen, is utilized.

The flow of inert gas through the evaporator is substantially continuous and steady though there is a pressure gradient from the inlet to the outlet portions thereof due to the throttling action of the liquid, particularly in rising conduits, on the gas stream. This insures substantially continuous uniform propulsion of liquid through the evaporator and continuous production of refrigeration whenever the refrigerating mechanism is operating.

While we have illustrated and described but a single embodiment of our invention it is to be understood that it is capable of expression in many other constructional forms and variations without departing from the spirit of the invention or the scope of the appended claims.

We claim:

1. Refrigerating apparatus comprising a pressure equalizing medium circuit including an upstanding evaporator and an absorber, a solution circuit including a boiler and said absorber, means for circulating a pressure equalizing medium through said pressure equalizing medium circuit in such direction that it flows upwardly through said evaporator and said absorber, a gas lift pump for elevating absorption solution into the top portion of said absorber, means diverting a portion of said pressure equalizing medium into said gas lift pump, means for liquefying refrigerant vapor generated in said boiler and for supplying the same to an intermediate portion of said evaporator, the arrangement being such that a portion of said liquid refrigerant flows downwardly through said evaporator in counterflow relationship to said pressure equalizing medium and the balance of said liquid is frictionally elevated through said evaporator by the gas stream flowing therethrough.

2. Refrigerating apparatus comprising a pressure equalizing medium circuit including an evaporator and an absorber, a solution circuit including a boiler and said absorber, means for propelling pressure equalizing medium through said pressure equalizing medium circuit, means for circulating solution through said solution circuit, said evaporator comprising a plurality of vertically spaced sections serially connected and connected to said pressure equalizing medium circuit in such fashion that pressure equalizing medium flows upwardly through said sections, means for liquefying refrigerant vapor generated in said boiler and for supplying the same to an intermediate portion of said evaporator, the arrangement being such that a portion of said liquid refrigerant flows downwardly through said evaporator in counterflow to said pressure equalizing medium as it evaporates thereinto and the remainder of said liquid refrigerant is carried upwardly through said evaporator section by said pressure equalizing medium as it evaporates thereinto.

3. That improvement in the art of refrigeration which includes the steps of evaporating liquid refrigerant into an inert gas flowing in counterflow relationship thereto in a first zone and evaporating liquid refrigerant into said inert gas as it is being conveyed thereby through a second zone and at temperature levels higher than that prevailing in said first mentioned evaporating zone.

4. Refrigerating apparatus including an evaporator comprising a plurality of vertically spaced

5 serially connected sections, means for propelling a pressure equalizing medium upwardly through said sections, means for supplying liquid refrigerant to said evaporator intermediate a pair of adjacent sections, the arrangement being such that a portion of the liquid flows downwardly counter to the gas stream into the lower of said pair of sections and the remaining portion of the liquid is carried by said gas stream upwardly into said upper pair of sections by the frictional drag of the gas stream flowing thereover.

5. That improvement in the art of refrigeration which includes the steps of propelling pressure equalizing medium through an evaporating zone, flowing one body of liquid refrigerant through said evaporating zone by the frictional drag exerted thereon by said pressure equalizing medium, flowing another body of liquid refrigerant in said evaporating zone counter to said pressure equalizing medium, and regulating the rate of flow of said pressure equalizing medium in accordance with ambient conditions.

6. That improvement in the art of refrigeration which includes the steps of condensing refrigerant to liquid phase by heat exchange with atmospheric air, supplying liquid to an evaporating zone, propelling a pressure equalizing medium through said evaporating zone and an absorbing zone, circulating an absorbent through said absorbing zone, rejecting the heat of absorption to the surrounding air, circulating liquid refrigerant through said evaporating zone in parallel flow relationship and in counterflow relationship with the pressure equalizing medium, and regulating the rate of flow of the pressure equalizing medium in accordance with the condition of the surrounding air.

7. Absorption refrigerating apparatus comprising an inert gas circuit including an evaporator and an absorber, power driven means for circulating an inert gas through said circuit, a solution circuit including a boiler and said absorber, means for supplying refrigerant generated in said boiler to said evaporator in liquid phase, said evaporator including a low section having a large diameter passageway therethrough, an upper section having a small diameter passageway therethrough, a riser conduit including interfitting extensions of each of said evaporator sections, the arrangement being such that liquid refrigerant is supplied to the extension of said section having a small diameter passageway therethrough adjacent its junction with said section of large diameter.

8. That improvement in the art of refrigeration which includes the steps of supplying a body of liquid to be evaporated to an intermediate portion of an evaporating zone, flowing a portion of such liquid downwardly in counterflow relationship to a low velocity stream of an inert pressure equalizing medium, and circulating the balance of said refrigerant upwardly through said evaporating zone by the frictional drag exerted thereon by a high velocity stream of inert gas flowing through said other portion of said evaporating zone.

9. Refrigerating apparatus comprising means for producing refrigerant vapor, means for condensing the vapor so produced, an evaporator including a portion of large cross-sectional area joined to a portion of small cross-sectional area which extends upwardly above at least a portion of said condensing means, means for supplying liquid from said condenser to said evaporator adjacent the junction of said portions of large

and small cross-sectional area, and means for propelling a pressure equalizing medium through said evaporator to circulate a portion of said liquid through said evaporator section of small cross-sectional area by the impetus imparted to the liquid by the high velocity gas stream flowing through said portion of small cross-sectional area.

10. An absorption refrigerating apparatus comprising an inert gas circuit including an evaporator and an absorber, a solution circuit including a boiler and said absorber means for liquefying refrigerant vapor generated in said boiler, said evaporator including a section of small cross-sectional area and a section of large cross-sectional area, means for circulating the inert gas through said evaporator with sufficient force to propel liquid refrigerant through said section of small cross-sectional area, and means for supplying refrigerant liquid from said liquefying means to said evaporator adjacent the junction point of said sections of different cross-sectional area, whereby a portion of such liquid flows through said section of large cross-section by gravity.

11. An absorption refrigerating apparatus comprising an inert gas circuit including an upstanding evaporator and an absorber, a solution circuit including a boiler and said absorber, means for liquefying refrigerant vapor generated in said boiler, said evaporator including an upper section of small cross-sectional area and a lower section of large cross-sectional area, means for supplying refrigerant liquid from said liquefying means to said evaporator adjacent the junction point of said sections of different cross-sectional area, and means for circulating the inert gas upwardly through said evaporator with sufficient force to propel liquid refrigerant through said section of small cross-sectional area, whereby a portion of the liquid refrigerant flows through said evaporator with the inert gas and another portion thereof flows through said evaporator counter to the direction of flow of the inert gas.

12. A combined liquid dividing and elevating device comprising a downwardly extending conduit, an upwardly extending conduit joined to said first mentioned conduit and of smaller cross-sectional area, means for propelling a gas through said conduits in a direction to flow first through said downwardly extending conduit and with sufficient force to propel liquid through said upwardly extending conduit but with insufficient force to propel liquid through said downwardly extending conduit, and means for supplying liquid to said conduits adjacent the junction point thereof.

13. An absorption refrigerating apparatus comprising an inert gas circuit including an evaporator and an absorber, a solution circuit including a boiler and said absorber, means for liquefying refrigerant vapor generated in said boiler, said evaporator including an upper substantially horizontal conduit section of relatively small cross-sectional area and a lower substantially horizontal conduit section of relatively large cross-sectional area, a riser conduit connecting said sections and including portions of large and of small cross-sectional area, means for supplying refrigerant liquid from said liquefying means to said evaporator adjacent the junction point of said sections of different cross-sectional area, and means for circulating the

inert gas through said evaporator with sufficient force to propel liquid refrigerant through said section of small cross-sectional area.

14. That improvement in the art of absorption refrigeration which includes the steps of expelling refrigerant vapor from solution by the application of heat thereto, liquefying the vapor so expelled, conveying a portion of the liquid into the presence of a stream of dense gas flowing with a velocity sufficient to propel the liquid as it is evaporating, flowing another portion of the liquid into the presence of a stream of dense gas flowing with a velocity insufficient to impart a propelling force to the liquid, and absorbing the refrigerant vapor from said bodies of gas by contacting the same with solution previously weakened by the expulsion of refrigerant vapor therefrom.

15. Absorption refrigerating apparatus of the pressure equalized type including an evaporator element in which a transfer of refrigerant vapor occurs between a refrigerant liquid and an inert pressure equalizing medium, an absorber element in which a transfer of refrigerant vapor occurs between an absorbing liquid and said inert pressure equalizing medium, means for producing refrigerant liquid and for supplying the same to said evaporator element, means for conveying absorbing liquid to and from said absorber element, one of said elements having a portion of large cross-sectional area joined to a portion of small cross-sectional area, and means for propelling the inert pressure equalizing medium through the portion of said one element of small cross-sectional area under sufficient pressure and velocity to propel the liquid therethrough as a transfer of refrigerant vapor is occurring between the liquid and the inert pressure equalizing medium, said one element being so arranged that liquid supplied thereto is supplied adjacent the junction of said portions of large and small cross-sectional area whereby the liquid flows through the portion of said one element of large cross-sectional area by gravity as a vapor transfer occurs between the liquid and the inert pressure equalizing medium.

16. Absorption refrigerating apparatus of the pressure equalized type embodying an element having a passageway in which an inert pressure equalizing medium is in intimate contact with a liquid to effect a transfer of a refrigerant vapor between the liquid and the inert pressure equalizing medium accompanied by a transfer of heat through the wall of said passageway, said element including a portion of large cross-sectional area designed for a gravity flow of liquid and a portion of small cross-sectional area joined to said portion of large cross-sectional area, means for propelling the inert pressure equalizing medium through said element with sufficient pressure and velocity to distribute liquid through said portion of small cross-sectional area and to pass into and out of the distributed liquid, and means for supplying liquid to said element adjacent the junction of said portions of large and small cross-sectional area whereby a part of the liquid is distributed through said portion of small cross-sectional area by the inert pressure equalizing medium and another part of the liquid flows through said portion of large cross-sectional area by gravity.
